UNITED STATES PATENT OFFICE.

GAITHER A. PLUNKETT, OF BAY POINT, CALIFORNIA.

DEVICE FOR MOVING FREIGHT-CAR DOORS.

Application filed February 10, 1927. Serial No. 167,340.

My invention relates to improvements in devices for moving freight car doors, and it consists in the combinations, constructions, and arrangements, hereinafter described and claimed.

An object of my invention is to provide a device for moving freight car doors, which makes use of manually controlled means for positively moving the door into closed or opened positions.

Further objects and advantages will appear in the following specification, and the novel features of the invention will be particularly pointed out in the appended claims.

My invention is illustrated in the accompanying drawing, forming a part of this application, in which—

Figure 1 is a side elevation of the device,
Figure 2 is an enlarged view of a portion of the device, and

Figure 3 is a vertical section thru a portion of the device.

In carrying out my invention, I make use of a door 1 having guide members 2 slidably receivable in a side rail 3. When the door is in closed position, it is adapted to abut against a door jam 4. The parts of the device, thus far described, form no part of my invention except in so far as they cooperate with the parts now to be described.

The lower part of the door is supported by grooved rollers 5 and 6 which ride upon a rail 7. The roller 5 differs from the roller 6 in that it has projections 8 or pins that are removably receivable in openings 9 in the top of the rail 7.

The rollers 5 and 6 are rotatably mounted in front and rear supports 10 and 11 respectively. The support 10 has cutaway portions 12 for exposing the lower portion of the rollers 5 and 6 and for forming retaining fingers 13 and 14.

The shape of the rail 7 is clearly shown in Figure 3, and it will be noted that the fingers 13 and 14 receive the outer edge 15 of the rail. The rail has a flange 16 for spacing the rail from the freight car wall 17, and the flange has downwardly extending lugs 18 for receiving bolts 19.

The openings 9 are spaced the required distance apart for receiving the pins 8 (see Figure 2). The walls of the openings, extending in the line of travel, are inclined downwardly as at 20 (see Figure 2). The pins engage with the inclined portions and

aid in moving the door since the pins ride upwardly on the inclined portions and thus automatically extricate themselves without impeding the progress of the door.

I provide means for positively rotating the roller 5 and this means comprises a lever 21 pivotally mounted upon the shaft 22, which supports the roller 5. A double ratchet wheel 23 is rigidly mounted upon the shaft 22 and is adapted to be intermittently rotated by a double pawl 24 pivotally secured at 25 to the lever 21.

From the foregoing description of the various parts of the device, the operation thereof may be readily understood. Assume that the door is in the position shown in Figure 1 and that it is desired to open the same. The double pawl 24 is swung from the position shown in Figure 1 into the position shown in Figure 2, and then the lever 21 is manually rocked back and forth for causing the roller 5 to intermittently rotate in one direction for opening the door. The lever 21 has a slot 26 therein for permitting the double pawl to be swung on either side of the lever 25. A guard 27 limits the movement of the lever. The openings 9 are provided in a little over one half the length of the rail 7, thus providing positive means for moving the door into complete opened or closed position. Any foreign matter lodging in the openings is forced out by the pins 8 as the roller 5 rides over the track 7. When the lever is in the full line position shown in Figure 1, the double pawl 24 will swing free of the double ratchet 23 and will permit the door 1 to be moved in the usual manner.

I claim:

1. In a device of the type described comprising a door, a supporting rail for said door having a plurality of openings therein, the walls of said openings being inclined, and a door supporting roller movable on said rail and having projections removably receivable in said openings.

2. A device of the type described, comprising a door, a supporting rail for said door, said rail having perforations, grooved door supporting rollers mounted on said rail, projections carried by one of said rollers and being receivable in said openings, a double ratchet connected to said last named roller, a lever, and a double pawl carried by said lever for rotating said ratchet in either direction.

3. In a device of the type described, comprising a door, a supporting rail for said door having a plurality of openings therein, the walls of said openings being inclined downwardly from the top surface of said rail, and a door supporting roller movable on said rail and having projections removably receivable in said openings, and manually controlled means for positively rotating said roller in either direction.

4. In a device of the character described, comprising a door, a supporting rail for said door, said rail having perforations, grooved door supporting rollers mounted on said rail, projections carried by one of said rollers and being receivable in said openings, supports for securing the rollers to the door, a ratchet connected to said last named roller, teeth on said ratchet having the opposite sides thereof tapered towards the center of said ratchet, a lever, a pawl pivotally secured on one end to said lever, projections disposed on opposite sides of the other end of said pawl, one of said projections to engage one side of said ratchet teeth when the door is being moved in one direction, the other of said projections to engage the opposite side of said ratchet teeth when the door is being moved in the opposite direction.

5. In a device of the character described, comprising a door, a supporting rail for said door, said rail having perforations, grooved door supporting rollers mounted on said rail, projections carried by one of said rollers and being receivable in said openings, supports for securing the rollers to the door, a ratchet connected to said last named roller,

teeth on said ratchet having the opposite sides thereof tapered towards the center of said ratchet, a lever, a pawl pivotally secured on one end to said lever, projections disposed on opposite sides of the other end of said pawl, one of said projections to engage one side of said ratchet teeth when the door is being moved in one direction, the other of said projections to engage the opposite side of said ratchet teeth when the door is being moved in the opposite direction, and means for holding said lever so as to support said pawl in a disengaged position.

6. In a device of the character described, comprising a door, a supporting rail for said door, said rail having perforations, grooved door supporting rollers mounted on said rail, projections carried by one of said rollers and being receivable in said openings, supports for securing the rollers to the door, a ratchet connected to said last named roller, teeth on said ratchet having the opposite sides thereof tapered towards the center of said ratchet, a lever, a pawl pivotally secured on one end to said lever, projections disposed on opposite sides of the other end of said pawl, one of said projections to engage one side of said ratchet teeth when the door is being moved in one direction, the other of said projections to engage the opposite side of said ratchet teeth when the door is being moved in the opposite direction, means for holding said lever so as to support said pawl in a disengaged position, said means to limit the operating radius of said lever.

In testimony whereof I affix my signature
GAITHER A. PLUNKETT
